CLAIM

I claim the ornamental design for a gripped wire connector with lined bumps, as shown and described.

DESCRIPTION

FIG. 1 is a front view for a gripped wire connector with lined bumps;

FIG. 2 is a right side view thereof;

FIG. 3 is a left side view thereof;

FIG. 4 is a top view thereof;

FIG. 5 is a bottom view thereof;

FIG. 6 is a back view thereof;

FIG. 7 is a front perspective view thereof;

FIG. 8 is a rear perspective view thereof; and,

FIG. 9 is a cross-sectional view thereof taken along section lines FIG.9-FIG.9 of FIG. 1.
 The broken lines in the figures represent portions of the article which form no part of the claimed design.

1 Claim, 9 Drawing Sheets
